UNITED STATES PATENT OFFICE.

IVAN LA MONTAGNE, OF SPRINGFIELD, MASSACHUSETTS, ASSIGNOR TO BAY STATE CORSET COMPANY, OF SPRINGFIELD, MASSACHUSETTS, A CORPORATION OF MASSACHUSETTS.

GARMENT OR WEARING-APPAREL, AND MORE PARTICULARLY TO CORSETS.

1,362,013.

Specification of Letters Patent. Patented Dec. 14, 1920.

Application filed February 24, 1919. Serial No. 278,570.

To all whom it may concern:

Be it known that I, IVAN LA MONTAGNE, a citizen of the United States of America, residing in Springfield, Hampden county, 5 Commonwealth of Massachusetts, have invented certain new and useful Improvements in Garments or Wearing-Apparel, and more particularly to Corsets, a specification of which follows.

10 This invention relates to improvements in garments or wearing apparel, and more particularly to corsets in which a pocket is permanently attached to one of the members composing the garment. The object 15 of the invention is to provide a pocket for the safe keeping of small articles as jewelry, and also to serve the purpose as a pad to protect the wearer against pressure caused by the clasp or connecting means on the 20 stays of the corset.

The invention, broadly considered, comprises a pocket formed of fabric, or other suitable material, which is permanently attached to one of the members or sections 25 at the front part of the garment and preferably adjacent one of the stays and having a flap portion to close the entrance to the pocket. This pocket is located over the clasp in order to prevent injury to the 30 wearer.

Referring to the drawings:

Figure 1 shows a sectional view of the front inside portion of an ordinary corset structure illustrating the stays and the connecting clasps with the flap of the pocket closed or hanging in a pendent position.

Fig. 2 is a sectional view on the line 2—2 of Fig. 1 showing the relative location of the pocket, the flap and the clasps which 40 are carried by the stays.

Referring to the drawings in detail: 1 and 2 designate respectively the two members or sections of the corset structure. The studs secured to one of the stays are indicated at 3, the stays being shown in section at 4 and the fabric, inclosing the stays, at 5. 6 designates the usual connecting clasp which engages the stud 3 to hold the sections 1 and 2 together. Referring to the 50 pocket construction, 7 designates the back portion of the pocket which is secured at one of its side edges directly to the section 1 as shown in Fig. 1, by means of the stitching or threads indicated at 8 and which are

located at the inner edge of the stay 4. 55 The pocket, it will be noticed, is wide enough to extend across the meeting edges of the two sections 1 and 2, and wide enough to coincide with the inner edge of the oppositely located stay to which the 60 clasps 6 are secured. It is closed by means of the flap or extension 9 of the back portion 7. As shown in Fig. 1, the flap is closed. In Fig. 2 it is shown open part way in order to give access to the entrance 65 opening 10, the upper edge of the front portion being below the upper edge of the back portion. The front surface of the flap 9 is preferably covered with some soft material, as plush, indicated at 11, which will 70 bear against the person as indicated by the dotted lines 12 in order to cushion the stays 4 as readily understood.

It will be seen that the pocket proper is preferably formed of a single piece of 75 fabric material, the front part of the pocket being indicated at 13, the fold at the bottom being indicated at 14 and that the closure or flap 9 is a continuation of the portions 13 and 14; or in other words, the 80 pocket is a one piece structure, the outer edges of which are stitched together as indicated at 8 and 15.

From this description it will be seen that the invention includes the double purpose 85 or object of furnishing a pocket for valuables and a pad for cushioning purposes.

What I claim is:

1. As an article of manufacture, a corset having two members, a pocket structure 90 thereof and having one edge only secured to one of the members by stitching the same on a line adjacent the inner edge of the front fastening of said member and of a width sufficient to extend across the front 95 meeting edges of the two members and over the other member an equal distance, a pendant or flap for closing the pocket structure and having its outer surface provided with a layer of soft material, said 100 flap being located on the inside of the corset with the plush surface toward the wearer, said pocket and flap serving as a pad for the wearer to prevent injury of the fastening devices of the corset. 105

2. A corset structure having two members, stays therefor, the combination, with one of the front stays thereof, of a pocket

secured thereto with an opening at its upper end and accessible from the inside of the corset and designed to extend across the space between the meeting edges at the 5 front part of the garment and having a pendant flap extending across the opening of the pocket and a continuation of the rear part of the pocket structure that is secured directly to one of the corset members, as 10 described.

3. An article of manufacture, a corset having two members, stays therefor, studs and clasps on the stays, a pad and pocket construction located at the upper front 15 meeting edges of the members and on the inner surface of the corset, said pad serving

as a pocket and comprising a single strip of fabric material that is folded between its ends, one of the folded portions of the strip being stitched directly to one of the 20 corset members only and near the front connecting stay of one member, another portion of the strip serving as a pendant or flap to close the opening at the upper end of the pocket, and the remaining portion of the strip serving as the front part or portion of the pocket proper, as described, the width of the pad and pocket extending across the meeting edges of the members and over the studs and clasps as 25 30 described.

IVAN LA MONTAGNE.
